UNITED STATES PATENT OFFICE.

JEFFERSON M. SHARP, OF OIL CITY, PENNSYLVANIA, ASSIGNOR TO NATIONAL TRANSIT PUMP & MACHINE CO., OF OIL CITY, PENNSYLVANIA, A CORPORATION OF PENNSYLVANIA.

PUMP CYLINDER AND MOUNT THEREFOR.

Application filed October 26, 1928. Serial No. 315,267.

This invention relates to a pump cylinder and a mount or support therefor, whereby a pump suitable for pumping hot fluids, and more particularly hot petroleum through the cracking coils, stills, etc. of a cracking plant, is produced.

As the art of cracking oils to produce gasoline is at present practiced very high temperatures are imparted to the oil, a temperature of 1000° F. being common.

Heretofore pumps employed in this service have their cylinders supported by a base or foot which is attached to the bottom wall of the cylinder, or is integral therewith, and because of this method of attachment, the expansion of the cylinder due to the heat of the oil being pumped has all been in the upward direction, with the exception of that portion of the expansion which takes place longitudinally of the cylinder.

This vertical, or upward expansion distorts the alinement of the pump organization and throws the axial line of the bore of the pump cylinder upward thus greatly interfering with the efficient operation of the pump and increasing its power requirement, also the wear upon the packing in the stuffing boxes.

It is the object, therefore, of this invention to supply a pump cylinder and a mount or support therefor of such character of construction and assembly that the walls of said cylinder will be free to expand radially, with respect to the axis of the bore of the cylinder, in all directions, in such manner that said longitudinal axis of said bore will always remain a neutral point uneffected by expansion or contraction; also that the longitudinal expansion and contraction of the pump cylinder may take place without in any way distorting or straining any portion of the pump organization.

In the accompanying drawings, I have illustrated one form of construction in which my inventive idea is mechanically embodied and has been found to be perfect in actual operation.

The construction shown in said drawings is substantially as follows:

Fig. 1 is one form of direct-acting steam pump embodying my invention.

Fig. 2 is a side elevation of the construction shown in Fig. 1.

Fig. 3 is an elevation of my improved cylinder-supporting base.

Fig. 4 is an end elevation of an assembly of my improved pump cylinder and its support.

Fig. 5 is a perspective view of my improved cylinder.

In said drawings, the pump cylinder is indicated by the numeral 1; 2 is the supporting base consisting of a unitary structure upon which said cylinder is mounted; 3 is the steam engine cylinder from which power is derived for the operation of the pump; 4, 4 are the tie rods whereby the pump cylinder is connected to the steam cylinder; 5 and 6 are the pump plungers; 7 and 8 are water-cooled stuffing boxes for said plungers; 9 and 10 are crossheads for the pump plungers and 11 and 12 are cross-head guides.

Referring especially to Fig. 4, it is pointed out that on each lateral face of the pump cylinder 1 and at a location which alines, 75 transversely of the cylinder, exactly with the center of the bore 13 of said cylinder, is formed a longitudinally extending seating face or projection 14 which is machined in and integral with the cylinder walls and 80 adapted to seat upon the supporting faces 15, 15 of the upwardly projecting arms 16, 16, of said supporting bases, 2, 2.

It is also pointed out that said cylinder 1 is not rigidly secured to said bases but 85 merely rests thereon; let it be noted that the gap of the base, as formed by and between said upwardly extending arms, and as indicated at the dimension *a* is somewhat greater than the width *b* of the cylinder, 90 whereby expansion spaces are provided at both sides of said cylinder as indicated in Fig. 4.

Because of the construction above specified the axial line of the bore of the cylinder, 95 as considered in relation to the expansion and contraction of said cylinder, remains always a neutral point relative to which expansion of the cylinder walls takes place radially in all directions without throwing the axis of the bore out of alinement with the co-operating members of the pump organization.

My improved construction also provides for and admits of linear or longitudinal expansion of said pump cylinder but inasmuch

as one end of said cylinder is connected by means of said tie rods 4 to the adjacent end of the steam engine cylinder 3, said linear expansion is in one direction, but this one direction expansion in no way disturbs the axial alinement of the pump cylinder, neither does it produce any other detrimental effect upon the pump organization.

I claim the following:

- 10 1. The combination of a pump cylinder and a mount therefor constructed and assembled together in such manner that the axial line of the bore of said cylinder maintains a neutral position when, owing to the heat of fluid being pumped, the walls of said cylinder expand and contract, said construction and assembly comprising a longitudinally extending, outwardly projecting ledge carried upon each side of said cylinder with a downwardly disposed seating, cylinder supporting face, which faces are in lateral alinement in the same horizontal plane with the axis of the bore of said cylinder, and a supporting structure for said cylinder comprising supporting members whereupon said supporting faces seat respectively so as to support said cylinder in said manner.
- 15 2. The combination of a pump cylinder and a mount therefor consisting of a supporting structure having upwardly-extending arms forming a gap therebetween for the reception of said cylinder, the upper ends of said arms forming seating faces, the sides of said cylinder each having an outwardly extending seating face which faces are transversely alined in the same horizontal plane with the axis of the bore of said cylinder whereby said cylinder is supported upon the seating faces of said arms, the construction and assembly of said cylinder and mount being such that the axial line of the bore of said cylinder is always a neutral point with respect to the expansion of the walls of said cylinder.
- 20 3. In a pump for hot liquids, the combination of a block provided with a cylinder bore and with longitudinally extending ledges one on each side thereof, each ledge having a downwardly disposed seating face coinciding in lateral alinement in the same horizontal plane with the longitudinal axis of said bore, and a unitary supporting structure for said block having upwardly disposed seating faces for said seating faces of the block, thus forming a mount for said block wherein it is free to expand radially in all directions from the longitudinal axis of said bore while said axis remains a neutral point.
- 25 4. In a pump for hot liquids, the combination of a block provided with a cylinder bore and with longitudinally extending ledges one on each side thereof, each ledge having a downwardly disposed seating face machined from said block, which seating faces are in the same horizontal plane with the longitudinal axis of said bore, and a unitary supporting structure for said block having upwardly disposed seating faces for the reception of said seating faces of said block whereon it is free to expand radially in all directions from the axis of said bore while said axis remains a neutral point.
- 30 5. In a pump for hot liquids, the combination of a block provided with a cylinder bore and with longitudinally extending ledges one on each side thereof, said ledges being integral with said block and having each a downwardly disposed seating face, which faces are in the same horizontal plane with the axis of said cylinder bore, and a supporting structure having corresponding upwardly disposed seating faces, thus forming a mount whereon said block is free to expand radially in all directions from the longitudinal axis of said bore while said axis remains a neutral point.

tion of a block provided with a cylinder bore and with longitudinally extending ledges one on each side thereof, each ledge having a downwardly disposed seating face coinciding in lateral alinement in the same horizontal plane with the longitudinal axis of said bore, and a unitary supporting structure for said block having upwardly disposed seating faces for said seating faces of the block, thus forming a mount for said block wherein it is free to expand radially in all directions from the longitudinal axis of said bore while said axis remains a neutral point.

4. In a pump for hot liquids, the combination of a block provided with a cylinder bore and with longitudinally extending ledges one on each side thereof, each ledge having a downwardly disposed seating face machined from said block, which seating faces are in the same horizontal plane with the longitudinal axis of said bore, and a unitary supporting structure for said block having upwardly disposed seating faces for the reception of said seating faces of said block whereon it is free to expand radially in all directions from the axis of said bore while said axis remains a neutral point.

5. In a pump for hot liquids, the combination of a block provided with a cylinder bore and with longitudinally extending ledges one on each side thereof, said ledges being integral with said block and having each a downwardly disposed seating face, which faces are in the same horizontal plane with the axis of said cylinder bore, and a supporting structure having corresponding upwardly disposed seating faces, thus forming a mount whereon said block is free to expand radially in all directions from the longitudinal axis of said bore while said axis remains a neutral point.

In testimony whereof I affix my signature.

JEFFERSON M. SHARP.
